US00D827317S

(12) **United States Design Patent** (10) **Patent No.:** **US D827,317 S**
Wehner (45) **Date of Patent:** ** *Sep. 4, 2018

(54) **HANGING CHAIR**

(71) Applicant: **Worldwide Creations, LLC**, Clio, MI (US)

(72) Inventor: **Scott D. Wehner**, Clio, MI (US)

(73) Assignee: **Worldwide Creations, LLC**, Clio, MI (US)

(*) Notice: This patent is subject to a terminal disclaimer.

(**) Term: **15 Years**

(21) Appl. No.: **29/585,817**

(22) Filed: **Nov. 29, 2016**

Related U.S. Application Data

(63) Continuation-in-part of application No. 29/572,467, filed on Jul. 28, 2016, now Pat. No. Des. 804,835.
